UNITED STATES PATENT OFFICE.

WILLIAM NICHOLAS, OF SOUTHPORT, CONNECTICUT, ASSIGNOR, BY MESNE ASSIGNMENTS, TO UNITED STATES GRAPHOTYPE COMPANY, A CORPORATION OF NEW YORK.

TYPE-BODY.

1,264,964.

Specification of Letters Patent. Patented May 7, 1918.

Application filed July 7, 1914. Serial No. 849,526.

To all whom it may concern:

Be it known that I, WILLIAM NICHOLAS, a subject of the King of Great Britain, residing in the town of Southport, county of 5 Fairfield, and State of Connecticut, have invented certain new and useful Improvements in Type-Bodies, fully described and represented in the following specification and the accompanying drawings, forming a part of 10 the same.

This invention relates to printers' type and has for an object to produce self-planing type bodies.

A further object of my invention is to produce body type, including both character type and spaces, none of which can rise above the general level of the form in which they are locked.

Among the chief annoyances experienced 20 by printers is that of having the type, and especially the quads and spaces, work up so as to mar the printed sheets, and in the case of character type, having the face mashed down and destroyed.

25 The form when locked in the chase preparatory to being placed on the press invariably requires that its surface be planed, that is, hammered down, which is usually done by means of a mallet and block, the 30 latter being termed a "planer," made of suitable material and flat upon the under surface which rests upon the faces of the character type. When one type stands higher than the rest, it will in this manner be 35 driven down to the proper level with probable injury thereto even though great care be observed in the process. It is often found, however, that the type cannot all be thus forced down to the one level, due in many 40 instances to the presence of foreign matter under the type, to remove which requires repeated locking and unlocking of the forms to remove the difficulty; or, in case of quads and spaces, because they are shorter than the 45 character type, they must therefore be forced below the plane of the printing surface one at a time, for which purpose the printers usually have at hand a tool known as a bodkin, which is specially designed to push 50 down a single type or a space.

Even after type have been carefully made ready for the printing press, the repeated vibrations under the heavy pressure of the platen or cylinder impacts upon the type

forms will sooner or later cause the spaces 55 and quads to rise up and leave their imprint upon the printed sheet.

Hence, it is the purpose of my invention to produce printers' type of all body sizes, which, when locked into a form, will automatically arrange themselves in proper order, with the character type on the required level for printing, and hold the spaces at the required distance below, and to retain both type and quads indefinitely in normal 65 relationship.

Type are usually cast with one or more recesses or nicks cut transversely across one side or edge, one over the other when a plurality of nicks are used. The nicks are concave in form, and in its general features my improved type body utilizes the founder's nick having upon the reverse side, corresponding in position and relative arrangement therewith, a rib or bead adapted to enter the nick of another type when placed in immediate contact therewith. The ribbed part need only protrude slightly, and is preferably made rounded, so that when brought into contact with a flat surface such 80 as a lead or a line of type not having a nick to correspond in position thereto its presence will not appreciably disturb the normal relationship of the lines composing a form 85 of type.

In the accompanying drawings of a preferred embodiment of my invention, Figure 1 is a perspective view of a type body provided with a rib or bead on one side; Fig. 2 is a side view of two of such bodies, as in 90 a form of type; Fig. 3 is an enlarged view of type bodies in similar arrangement showing relative position of the bead and nick in contiguous type.

On the side of the type 1 opposite to that 95 having the usual nick 2 I construct a rib or bead 3 preferably of a semi-circular cross-section, which is, similarly to the construction of the nick disposed transversely the full width of the character and is formed at 100 exactly the same distance from the bottom end of the type body as is the nick, the concavity of which likewise is of preferably semi-circular form. The half round curvature of the nick both at its upper and lower sides forms for a short distance from the surface of the type to which it relates a substantially perpendicular surface relatively

- to the vertical axis of the type, as at 4 in Fig. 3, and hence the corresponding upper or lower sides of the rib 3 when it is held within the nick 2 as in a locked form, will 5 engage the corresponding perpendicular surface 4 of the nick in the direction in which the rib position moves. Consequently the rib 3 should be constructed to prevent the type from rising uniformly at either the 10 bottom or top surface of the nick 2. In the drawings as in practice, I have constructed the ribs 3 to contact the lower surface of the nicks and to that extent would consider that as the preferred form of my invention. 15 Having thus described my invention, what I claim is:
1. A font of type having bodies provided with nicks in the sides thereof corresponding with the bottom of the character face thereon, minute ribs projecting from the sides corresponding with the top of the character thereon, and adapted to contact an edge of said nick whereby one of said type will hold the other in a fixed position relatively thereto.
  2. A font of type with nicks in one side of the body thereof, minute ribs projecting

from the opposite side, and located at a point to contact one or the other edge only of said nicks, substantially in the manner 30 shown.

3. A font of type having bodies provided with nicks in the side thereof corresponding with the bottom of the character face thereon, ribs projecting slightly from the side 35 similarly corresponding with the top of the characters thereon, said nicks being formed of larger diameter than the width of said rib, substantially as shown.

4. A font of type with nicks in one side 40 of the body thereof, minute ribs projecting from the opposite side and located at a point to contact one or the other edge only of said nicks, the height of said ribs being insufficient to disturb the alinement of the type to which it relates when composed in a form adjacent plain type surfaces.

In testimony whereof, I have hereunto set my hand in the presence of two subscribing witnesses.

WILLIAM NICHOLAS.
